CONTAINER AND CLOSURE THEREFOR

Herman Carew, Easton, Pa., assignor to Dixie-Vortex Company, Easton, Pa., a corporation of Delaware

Application August 8, 1936, Serial No. 95,023

2 Claims. (Cl. 229—47)

My invention relates to new and useful improvements in a container and closure therefor and more particularly to a closure cap, preferably of cardboard or similar relatively stiff material, adapted to be applied over the open mouth of a container and secured in position against accidental displacement but adapted to be readily removed when it is desired to consume or otherwise remove the contents of the container, the container being preferably formed of paper or similar material.

The principal object of the invention resides in the provision of a container, as stated, preferably of paper, having an outwardly extending projection or bead around the normal open mouth portion thereof, and a closure, of cardboard or similar material, in the form of a disc having flexible or bendable members connected thereto and normally projecting horizontally beyond the edge thereof, but adapted to be bent into engagement around and beneath the outwardly extending projection around the mouth portion of the container.

Another object of the invention consists in the provision of a closure disc of the character described of a diameter adapting the same to be engaged with the edge portion of the container surrounding the mouth and to overlie the normally open end of the container, said closure being provided with circumferentially spaced bendable members, preferably formed of wire, which normally overlie a face portion of the closure and extend horizontally beyond the edge portion thereof, these bendable members being adapted to be bent downwardly and inwardly into engagement with a projecting portion of the container to normally hold the closure into tight engagement with the edge portion of the container but adapting the closure to be readily removed when desired.

A further object of the invention resides in the formation of a closure disc or cap having members connected thereto whereby the cap or disc may be secured to a container, said members normally projecting horizontally beyond the edge of the closure disc or cap but adapting the caps or discs to be readily stacked to preserve space or be positioned within a suitable container.

With the above and other objects in view, which will appear as the description proceeds, my invention consists in the novel details of construction, and arrangement of parts, described in the following specification and illustrated in the accompanying drawing, and while I have 55 illustrated and described the preferred embodi-

ments of the invention, as they now appear to me, it will be understood that such changes may be made as will fall within the scope of the appended claims.

In the drawing:—

Fig. 1 is a top plan showing a closure disc or cap with the connecting members projecting horizontally therefrom in normal position.

Fig. 2 is a side elevation showing a container with a closure disc or cap resting on the mouth portion thereof with the connecting or securing members in their normal or horizontal position before being bent.

Fig. 3 is a top plan of a closure disc or cap in position upon a container with the connecting or securing members in engaging position.

Fig. 4 is a side elevation, partly in vertical section, showing the closure cap or disc secured in position on the container.

Fig. 5 is a fragmental sectional detail showing in bottom plan a closure disc or cap secured in position;

Fig. 6 is a fragmental transverse vertical section, with parts in elevation, showing one of the securing members in engagement with the projecting portion of a container.

Fig. 7 is a fragmental side elevation showing a slightly modified form of closure disc or cap in position on a container, with the securing members in their original horizontal position; and

Fig. 8 is a fragmental transverse vertical section, with parts in elevation, of the modified form of the invention illustrated in Fig. 7, one of the securing members being shown bent in engagement with the projecting portion of the container.

In the drawing 1 indicates a container, preferably of paper, in the form of a cup having a tapered wall portion with an inserted bottom 2 of desired formation. The lower edge portion of the body is turned inwardly as shown more particularly in Fig. 4 of the drawing and the upper edge or mouth portion of the body is rolled outwardly to provide an outwardly extending bead or projection 3.

My improved form of closure disc or cap is preferably formed of cardboard or similar material and is shown at 4. This disc or cap will be of a diameter permitting it to rest upon the normally open mouth portion of the container as shown more particularly in Figs. 2, 4 and 6 of the drawing and in snug engagement therewith. For securing the closure disc or cap to the container I provide a plurality of flexible or bendable

members carried by the disc or cap and adapted to be engaged around the bead or projection 3 of the container. In the drawing I have illustrated these flexible or bendable members 5 as being formed of wire with a portion of the arms 6 overlying the face of the disc or cap while the remaining portion or portions of the members project beyond the edge of the disc or cap as shown more particularly in Fig. 1 of the drawing. The inner ends of the arms 6 are bent downwardly as shown at 7, Fig. 6, through openings 8 formed in the disc or cap and then outwardly as shown at 9. This forms a connection between the flexible or bendable members and the disc or cap and by having these flexible or bendable members project horizontally it will be understood that a plurality of the closures may be arranged in stack-formation either on a suitable support or in a suitable container. While I have shown and described the flexible or bendable members as being formed of wire it will be understood that they might be formed in other ways such as by securing a thin metal plate or the like to the disc or cap. However, by providing the members of wire they may be easily bent and cover a relatively wide surface around the projection or bead 3 of the container.

In Fig. 1 of the drawing I have illustrated a closure in its normal form with the flexible or bendable members 5 extending horizontally to a point beyond the edge of the disc or cap and with portions of the arms thereof overlying the face of the disc or cap. After the container has been filled with the desired commodity the closure may be positioned as shown more particularly in Fig. 2 of the drawing and then the flexible or bendable members 5 will be bent into the position shown more particularly in Figs. 4, 5 and 6 of the drawing around and under the projection or bead 3 of the container. Where this has been done the closure disc or cap will be securely held with respect to the container but when it is desired to eat or remove the commodity within the container the flexible or bendable members may be engaged and bent away from the projection or bead 3 to permit ready removal of the closure from the container.

While in the drawing I have illustrated four of the circumferentially spaced securing or connecting members 5 it will be appreciated that other numbers of these members may be used as found expedient in use. It will also be seen that the flexible or bendable members are of such a width as to engage beneath the projection or bead of the container for a relatively wide space circumferentially thereof.

In Figs. 7 and 8 of the drawing I have illustrated a slightly modified form of my invention in which the peripheral edge of the closure disc or cap 10 is curved downwardly as shown at 11 to extend partly around and conform to the curvature of the bead or projection 3 of the container 1. In this form of the invention the flexible or bendable securing members 12 are of a construction similar to the members 5 of the other form shown in Figs. 1 to 6 inclusive and normally project horizontally from the disc or cap and are adapted to be bent around the bead or projection 3 as shown in Fig. 8.

Having fully described my invention what I claim as new and desire to secure by Letters Patent is:—

1. In combination with a container formed of paper or other fibrous material and having an outwardly directed readily compressible rounded bead at its normally open mouth, of a closure 20 including a disc of fibrous material and of a diameter to permit it to be seated on the upper surface of the rounded bead and a bendable member secured to the disc and normally projecting horizontally beyond the marginal edge thereof with a portion extending parallel with the disc, said bendable member being adapted to be bent around the rounded bead of the container and into engagement with the under surface thereof, the engagement of the bendable member with the 30 bead drawing the disc into tight seating engagement with the compressible bead to provide a tight seal between the closure and container.

2. In combination with a container formed of paper or other fibrous material and having an outwardly directed readily compressible rounded bead at its normally open mouth, of a closure 25 including a disc of fibrous material and of a diameter to permit it to be seated on the upper surface of the rounded bead, the marginal edge 40 of the disc being downwardly curved to conform to the curvature of the upper portion of the bead only and not to extend around or under the bead, and a bendable member secured to the disc and normally projecting horizontally beyond the marginal edge thereof with a portion extending parallel with the disc, said bendable member being 45 adapted to be bent around the rounded bead of the container and into engagement with the under surface thereof, the engagement of the 50 bendable member with the bead drawing the disc into tight seating engagement with the compressible bead to provide a tight seal between the closure and container.
